[57] CLAIM

The ornamental design for an exerciser for pets, as shown and described.

DESCRIPTION

FIG. 1 is a perspective view of a exerciser for pets showing my new design according to a first preferred embodiment; FIG. 2 is a left side view thereof, with the right side view being a mirror image;

FIG. 3 is a front view thereof;

FIG. 4 is a rear view thereof;

FIG. 5 is a top view thereof;
FIG. 6 is a perspective view of a exerciser for pets showing my new design according to a second preferred embodiment;

FIG. 7 is a left side view thereof, with the right side view being a mirror image;

FIG. 8 is a front view thereof;

FIG. 9 is a rear view thereof;

FIG. 10 is a top view thereof;

FIG. 11 is a perspective view of a exerciser for pets showing my new design according to a third preferred embodiment;

FIG. 12 is a left side view thereof, with the right side being a mirror image;

FIG. 13 is a front view thereof;

FIG. 14 is a rear view thereof; and,

FIG. 15 is a top view thereof.
